To all whom it may concern:

Be it known that I, David Galambossy, a citizen of the United States and a resident of Youngstown, Mahoning County, Ohio, have invented a new, original, and ornamental Design for Golf Putter, of which the following is a specification, reference being had to the accompanying drawing, forming a part hereof.

Fig. 1 is a front elevational view of a golf putter, showing my new design.

Fig. 2 is an end elevational view thereof; and

Fig. 3 is a top plan view thereof.

The dotted line showing of a fragmentary portion of a club shank in Figs. 1 and 2 is for illustrative purposes only.

I claim:

The ornamental design for a golf putter, as shown and described.
